UNITED STATES PATENT OFFICE.

FRANK A. BURNHAM, OF BATTLE CREEK, MICHIGAN, ASSIGNOR OF ONE-HALF TO DORR B. BURNHAM, OF SAME PLACE.

STEAM-ENGINE.

SPECIFICATION forming part of Letters Patent No. 544,476, dated August 13, 1895.

Application filed October 30, 1894. Serial No. 527,438. (No model.)

To all whom it may concern:

Be it known that I, FRANK A. BURNHAM, a citizen of the United States, residing at Battle Creek, in the county of Calhoun and State of Michigan, have invented certain new and useful Improvements in Steam-Engines; and I do hereby declare the following to be a full, clear, and exact description of the invention, such as will enable others skilled in the art to which it appertains to make and use the same.

My invention relates to improvements in steam-engines, and particularly to improvements in the mode and means of automatically operating the main valve of the engine.

The invention is applied to direct-acting steam-pumps, as shown in my Patent No. 519,857, dated May 15, 1894, but it is equally applicable to all reciprocating-piston engines.

The invention consists in the combination, in an engine of the character above indicated, of a valve-chest and cylinder, having independent passages leading from steam-chambers in the ends of said chest to exhaust, and steam-actuated valves or gates arranged in or across said passages.

It also consists in other combinations, hereinafter described and claimed.

In the drawings, Figure 1 is a central longitudinal section through the steam-chest and cylinder of an engine, showing the arrangement of my improvements in dotted lines. Fig. 2 is a plan of the cylinder adjacent to the valve-chest. Fig. 3 is a cross-section on the line 3 3 of Fig. 1. Fig. 4 is a longitudinal section on the lines 4 4 of Fig. 3.

A is the cylinder; B, the piston; C, the valve-chest, and D the valve of an ordinary piston engine. The cylinder A is provided with the usual steam ports, passages, and cavities, the inlet-passages being seen at a and a', the exhaust-passages at b, and the cavities at o and o'. The piston is provided with the usual packing-rings. The valve-chest C is attached to the cylinder by bolts in a well-known way and contains a piston for operating the main valve D. This piston is provided with heads F and F' at opposite ends thereof, which fit in chambers G G' in the valve-chest, and these heads have constricted steam-ports d d through them. The stem

connecting the two heads carries collars c c, between which the main valve is held and its movement controlled.

H is the induction-pipe for conducting steam from generator to steam-space I of the steam-chest. Leading from the outer ends of the chambers G and G' to exhaust b are passages g and g' to intermittently permit the escape of steam from the chambers behind one head of the valve-operating piston.

J and J' are piston valves or gates having annular grooves f f' arranged so that the grooves will alternately register with exhaust-passages g g'. These pistons or gates are arranged at one side of the cylinder in such position that the main engine-piston alternately passes them just before the completion of its stroke. Leading from the main cylinder to one end of these pockets, in which the pistons J J' are fitted, are ports k k', and leading from the extremities of the main cylinder to the other end of the pockets in which such pistons or gates are fitted are also ports P P'.

To avoid having the grooves f f' closed at any time I make branches m m' in the exhaust-passages g g'. This provides for exhausting the steam from the grooves. The valve D has the usual cavities n n'.

In operation, the main engine-piston having just completed its stroke to the right, steam passes from the main cylinder through port k' and raises valve J' and brings the groove f coincident with the exhaust-passage g' and exhausts the steam in chambers G' faster than it can flow through small port d', and the piston-head F, being exposed to full steam-pressure, is carried to the right and carries the main valve D with it. The cavity n in the valve now makes communication with steam-port a and exhaust-port b and exhausts the steam from main cylinder A. The cavity n' now communicates with the steam-port a' and the cavity o' in the cylinder-face, and steam is admitted to the cylinder through port a'. Steam will now flow through passage P' to the top of the valve or gate J' and force it down and close the exhausts through g'. The valve-driving piston is now balanced under an equal pressure at both ends.

Having described my invention, what I claim as new is—

1. In a steam engine the combination of a valve operating piston, having recessed heads and constricted ports, a steam chest having independent exhaust passages leading from 5 end chambers thereof to main exhaust and steam actuated gates or valves arranged across the passages substantially as described.

2. In a steam engine the combination of a steam chest having independent passages 10 from end chambers of said chest to main exhaust, gates or valves in said passages and passages from the main cylinder leading to opposite ends of the valves substantially as described.

15 3. In a steam engine the combination of a steam cylinder having valve or gate pockets arranged at one side of the main piston open-

ing, and having ports leading to one end of the pockets and ports leading from the extremities of the cylinder to the other end of 20 the pockets, a valve chest having independent exhaust ports leading from end pockets to main exhaust a valve operating piston having recessed heads for separating the valve chamber into compartments and having constricted ports and piston valves or gates for opening and closing the exhaust ports. 25

In testimony whereof I affix my signature in presence of two witnesses.

FRANK A. BURNHAM.
